UNITED STATES PATENT OFFICE.

TURNER D. BOTTOME, OF INDIANAPOLIS, INDIANA.

CARBURETER.

1,190,715.

Specification of Letters Patent. Patented July 11, 1916.

Application filed August 27, 1914. Serial No. 858,798.

To all whom it may concern:

Be it known that I, TURNER D. BOTTOME, a citizen of the United States, residing at Indianapolis, in the county of Marion and State of Indiana, have invented a new and useful Carbureter, of which the following is a specification.

It is the primary object of my invention to increase the mileage of automobiles for a given quantity of fuel, and to enable lower grades of fuel to be used for internal combustion engines.

It is my further object to render more nearly uniform the explosive mixture produced by a carbureter at different rates of carbureting, to improve the fuel volatilization, to compensate automatically the rate of fuel supply for differences in carbureter temperature so as to maintain the quantity of fuel constant for a given carbureter adjustment regardless of the carbureter temperature, to simplify the construction of the controlling and connecting mechanism for the air and fuel valves, to avoid that eddying of the various fluid currents in the carbureter which so markedly reduces carbureter efficiency, and to minimize those changes in the explosive mixture which are produced by wearing of the carbureter parts.

The accompanying drawing illustrates my invention.

Figure 1 is a horizontal section, substantially on the line 1—1 of Fig. 2, through a carbureter embodying my invention, with some of the parts removed; Fig. 2 is a central vertical section through such carbureter, substantially on the line 2—2 of Fig. 1; Fig. 3 is a somewhat reduced section on the line 3—3 of Fig. 1, showing the construction of a lamp which I may use in connection with my carbureter; Fig. 4 is a detail showing the construction of the air valve and its operating mechanism; Fig. 5 is a much enlarged view of the point of an improved needle for the needle valve; and Fig. 6 is an enlarged view of the remainder of the fuel nozzle for coöoperating with such needle.

The carbureter body comprises an inner tube 10 and a surrounding outer tube 11 integrally connected by a top 12 and a bottom 13 to form an annular chamber 14, which has an inlet opening 15 near the top and a discharge outlet 16 near the bottom for suitable heating gases, such as the exhaust gases from the associated engine. Surrounding

the inner tube 10 at an intermediate point in its length is a smaller annular chamber 17, formed by walls 18 and connected to the atmosphere by a tube 19 which passes through the outer tube 11. The inner tube 10 is provided with a slot 20 which extends entirely around it and connects the interior of such tube with the chamber 17. Slidably fitting within the tube 10, which is smooth inside and of substantially the same diameter throughout its length, is a sleeve 21, provided with slots 22 which coöperate with the slot 20 to admit a controlled flow of air to the tube 10. The shape of the slots 22 and the reason therefor will be brought out more fully hereinafter. The sleeve 21 is fixed on the upper end of a sliding shell 23, as by being screw-threaded thereon, the sliding shell 23 fitting slidably within the tube 10 and being contracted at its upper end to fit closely around a relatively long and slender tube 24 which extends lengthwise through the shell 23 and is provided at its lower end with a head 25; the shell 23, tube 24, and head 25 providing between them an annular space in which is located a suitably insulated heating coil 26. The supply wires 27 for the coil 26 pass out through openings 28 near the upper end of the shell 23. The inner surface of the tube 24 is made as smooth as possible. A cap 29 is screwed on to the projecting threaded upper end of the tube 24, and by bearing against the upper end of the shell 23 clamps the parts 23 and 24 firmly together so that such parts move as a unit, there being enough slack in the wires 27 to permit this. In order to move this movable unit, it is provided with a circumferential groove 30, which receives an eccentric pin 31 on a transverse shaft 32 operable by a lever 33 connected in any suitable way to the desired control point. By turning the lever 33, the unit 23—24 is shifted vertically.

The lower end of the tube 24 has a projection 35, which fits slidably within an annular opening 36 in the upper end of a plug 37 screw-threaded into the lower end of the tube 10. The annular opening 36 surrounds a projecting tube 38 integral with the plug 37, and within the tube 38 is mounted a tube 39 of some material having a higher coefficient of expansion than has the plug 37 and the tube 10. The tube 39 is conveniently of hard rubber if the parts

2

37 and 10 are of brass. In order to hold the tube 39 in place, its lower end 40 is conveniently screw-threaded into a suitable socket in the plug 37, so that relative movement between the parts 37 and 38 under change of temperature will be greatest at their upper ends, their lower ends being relatively fixed. The upper end of the tube 39 has screw-threaded within it or otherwise fixed to it a brass plug 41, in the upper end of which is a recess for receiving a small annular jewel 42, conveniently of sapphire, which is substantially not effected by wear, which jewel forms the fuel valve seat. A continuous opening 43 extends centrally through the plug 37, tube 39, plug 41, and jewel 42, for supplying kerosene, gasoline, or other fuel, the lower end of the plug 37 being suitably screw-threaded for attachment to a source of fuel supply, as by a pipe 45 in which is a valve 46. The lower end 35 of the sliding member 23-24 surrounds the tube 38, but is slightly spaced therefrom, and such lower end 35 is conveniently taperingly countersunk so that the interior of the tube 24 opens at its lower end to an oblique passage 44 extending through the plug 37 into the annular opening 36. The cap 29 has a finely-threaded central opening receiving the upper end of a depending needle 50, the point at the lower end of which projects into the opening in the jewel 42 to form therewith a fuel valve. The needle proper is preferably of steel or some other hard metal, but it has a long shank 51 which extends through nearly the full length of the tube 24 and is of some soft, nonresilient metal, such as lead or soft copper, which will yield transversely to allow the needle point to center itself in the bore of the jewel 42 and will not spring back materially to displace the needle from such centered position. Moreover, the shank 51 is preferably of some material which has a greater coefficient of expansion than has the body of the carbureter, as is the case if such shank is lead. As a result of the greater coefficient of expansion of the parts 39 and 51 than of the body of the carbureter, the tendency for the needle 50 to move from or toward its valve seat 42 upon an increase or decrease of temperature respectively, because of the expansion of the carbureter body, is compensated for or over-compensated for; as when there is a change in length of the body of the carbureter tending to separate or bring together the parts 50 and 42 there is an equal or greater change in length of the parts 39 and 51 tending to bring together or separate such parts respectively. Preferably there is an over compensation, because of the greater fluidity and volatility of the fuel under increased temperatures, as thereby the amount

of fuel supplied may be maintained constant. Preferably I make both the parts 39 and 51 of material having a greater coefficient of expansion than has the body of the carbureter, but the same result in kind can be obtained by making but one of these parts of such material having a greater coefficient of expansion.

The needle 50 is moved vertically with the sleeve 21 and the sliding units 23-24, as the shaft 32 is turned. The point of the needle 50 is a long slender point, so that the needle may have a very considerable vertical movement with its lower end remaining continuously within the jewel 42. The needle point preferably has several different tapers at different parts of its length, (three being shown,) as is clear from Fig. 5, the lowest portion of the needle consisting of a cone 55 of comparatively small taper, though the largest taper of any part of the needle, above this cone 55 being a conical frustum 56 of less taper, which frustum has above it another frustum 57 of still less taper, the elements of this latter frustum being at but a slight angle to those of the cylindrical needle portion just above it. The bore of the jewel 42 is equal in diameter to an intermediate part of the frustum 57, so that there is no opening when the needle is inserted into the jewel to this extent; but the needle is set so that it is never inserted into the jewel quite to this extent, to avoid wear. As the needle is withdrawn from the jewel, the increments of the opening thereby provided are annuli of constantly decreasing radius, but because of the triple taper of the needle point the widths of these annular increments per unit of linear movement of the needle is increased as the upper movement of the needle continues, so as to maintain more nearly uniform the increments of opening per unit of needle movement. By changing the tapers of the parts 55, 56, and 57, the increments of valve opening per unit of needle movement may be made anything desired at different points of the needle movement.

The shape of the openings 22 is empirically made to accord with the tapers given the parts 55, 56, and 57 of the needle 50, so that the size of such openings at a number of measured positions is made proportional to the volume of fuel discharged by the fuel valve under a given head of fuel for corresponding needle positions; probably because of the length of the tube 24, and the consequent close approach to atmospheric pressure around the fuel nozzle, this is found to make a substantially proportional mixture of air and fuel for all degrees of suction. Ordinarily I make the upper edge 61 of each slot 22 oblique to the lower edge of the slot 20 so as to provide an increasing rate of

opening of the air valve as the sleeve 21 moves upward in the first part of its movement, the ends 62 usually being square to make the middle part of the air valve movement one with a uniform rate of opening, and the bottoms 63 of such openings usually being oblique to the bottom edge of the slot 20, but in the reverse direction from the top edge 61 thereof so as to make the last part 10 of the upward movement of the air valve one in which the rate of change of the air opening is a decreasing one. The particular shape of the openings 22 will vary with the particular shape of the needle point, so as to 15 maintain a substantially uniform volumetric proportion between the air and fuel, but in nearly every case the upper edge and conveniently the lower edge of each of such openings is oblique to the lower edge of 20 the slot 20. As shown, the obliquity of both edges is part one way and part the other, making the openings somewhat diamond shaped.

The cap 29 fits into the lower end of a 25 wire coil 65 wound on the inside of a tube of insulation 66, this coil and tube conveniently being carried by the shell 23. Thus leading-in wires 67 for this coil pass through openings in a ring of insulation 68, which 30 is interposed between the inlet opening of the manifold 69 to which the carbureter is connected and the attaching flange 70 of the carbureter, such attaching flange conveniently being a separate piece from the carbureter body and being provided with a neck 35 71 which is screwed into the upper end of the tube 10, the inner surface of such tube and the inner surface of the rings 68 and 70 conveniently forming a smooth surface, as 40 shown. The leading-in wires 67 conveniently supply both the coil 65 and the coil 26, being connected to the supply wires 27 for the latter, these two coils being connected in any desired relationship to each other, 45 such as the series relationship shown. The tube 66 is open at the upper end to the surrounding space within the tube 10, and the cap 29 is provided with a number of openings 75 for supplying gasoline to the 50 lower end of such tube from the space within the tube 24. These openings 75 and the passage 44 and tubes 24 are of proper area to admit just enough air for the associated engine to run idle at low speed, and the 55 needle 50 is set so that when it is in its lowest position, with the air valve 20—21 closed, it does not quite shut off the supply of fuel but admits enough fuel to mix in proper proportions with the air in the tube 60 24 to run the engine idle.

In operation, fuel, such as gasoline or kerosene, or even lower grades of oil, is supplied to the passage 43, and such fuel is drawn from the first nozzle into the interior

of the tube 24. Here it is mixed with air 65 entering through the passageway 44, this air being large in quantity as compared with the fuel but small in quantity as compared with the air supplied through the openings 22, when the latter are open; and this air 70 from the passageway 44 and the fuel pass together at a high velocity up through the tube 24 to the space under the cap 29, and then pass through the openings 75 in such cap at a still higher velocity into the lower 75 end of the tube 66, continuing up through this latter tube and in contact with the coil 65 to the upper end thereof and then passing therefrom into the open space within the tube 10. In the meantime air has been entering through the tube 19, slot 20, and slots 22 into the space within the tube 10, and this air is drawn upward by the engine suction around the outside of the tube 66, this latter air being mixed with the mixed air and fuel 80 from the inside of the tube 66 as they pass beyond the upper end of the latter. By reason of the high velocity of the fuel as it passes through the openings 75, such fuel is very finely divided, and this fuel is heated 85 both before and after passing such openings 75 by the coils 26 and 65, so that when it emerges from the upper end of the tube 66 it is practically in the form of vapor, so that it becomes intimately mixed with the 90 air to form a readily explosive mixture. This air is heated, as is also the fuel, by the exhaust gases passing through the chamber 14, which also helps to make a better explosive mixture. The opening of the fuel 100 and air valves is controlled by the shaft 32, which shifts vertically the sliding member 23—24 to move the cylinder 21 of the air valve and the needle 50 of the fuel valve simultaneously upward or downward, thus 105 controlling the amount of fuel and air.

The passages for the various streams of fluid through the carbureter are all smooth passages, as furnished by the inside of the tubes 10 and 24, and practically by the inside of the coil of wire 65 which is preferably made of wire of rectangular cross section. As a result, there are no sharp corners, save at the openings 75 where they are necessary to provide for the sudden increase 110 in the speed of the fuel, and so the usual eddying which takes place in carbureters at the cost of their efficiency is practically totally avoided. The air and fuel valves are rigid with each other, so that they move together in a straight line. The sliding member which carries the movable parts of the air and fuel valves may turn in any way within the tube 10 without producing any 115 effect, as the slot 20 extends entirely around such tube and no particular position of the sleeve 21 is essential. The parts are prevented from getting out of adjustment by 120

reason of the practically unwearable steel needle point and sapphire valve seat and the fact that the needle is never fully seated, and the needle is rendered self centering by 5 reason of its soft metal shank. Finally, the fuel and air are at all times in uniform volumetric proportion.

If desired, a lamp 80 may be provided for 10 keeping the carbureter constantly warm and thus facilitating starting, especially with low grades of fuel. When such a lamp is used, it conveniently takes the form shown in Figs. 1 and 3, the flame and hot gases 15 from the lamp passing up through a flue 81 provided by walls 82 within the chamber 14 and between the vertical planes of the inlet and exhaust pipes 15 and 16, and passing out from the top of the flue 81 by a horizontal pipe 83 which is turned upward at its 20 outer end 84 so that it discharges under a hood 85, beneath which hood 85 and spaced therefrom is a second hood 86 under which opens an upwardly-extending tube 87 surrounding the up-turned part 84 of the tube 25 83 and extending downward to supply air to the flame of the lamp 80. The operation of the lamp is substantially unaffected by any wind to which it may be exposed.

I claim as my invention:

30 1. In a carbureter, the combination of a tube having a lateral air inlet aperture, a member slidable longitudinally within said tube and provided with a perforated part coöperating by relatively oblique edges with the aperture in the tube to control the admission of air thereto, said member also being provided with a longitudinal passage, with a needle mounted in said longitudinal passage, and with a cap carrying said needle 35 40 and located at the top of said passage and provided with restricted perforations for allowing the flow of fluid from said passage to the space within said tube, and a fuel nozzle with which said needle coöperates to 45 control the supply of fuel to said passage.

2. In a carbureter, the combination of a tube having a lateral air inlet aperture, a member slidable longitudinally within said tube and provided with a perforated part 50 coöperating with the aperture in the tube to control the admission of air thereto, said member also being provided with a longitudinal passage, with a needle mounted in said longitudinal passage, and with a cap 55 located at the top of said passage and provided with restricted perforations for allowing the flow of fluid from said passage to the space within said tube, and a fuel nozzle with which said needle coöperates to 60 control the supply of fuel to said passage.

3. In a carbureter, the combination of a tube having a lateral air inlet aperture, a member manually slidable longitudinally within said tube and provided with a per-

forated part coöperating with the aperture 65 in the tube to control the admission of air thereto, said member also being provided with a longitudinal passage, and with a needle mounted in said longitudinal passage, and a fuel nozzle with which said 70 needle coöperates to control the supply of fuel to said passage, said nozzle having an opening in its upper surface and said needle projecting into said opening.

4. In a carbureter, the combination of a 75 tube having a lateral air inlet aperture, a member slidable longitudinally within said tube and provided with a part coöperating by relatively oblique edges with the aperture in the tube to control the admission of air 80 thereto, said member also being provided with a longitudinal passage, and with a needle mounted in said longitudinal passage, and a fuel nozzle located in said passage and with which said needle coöperates to control the supply of fuel to said passage.

5. In a carbureter, the combination of a tube having a lateral air inlet aperture, a member manually slidable longitudinally within said tube and provided with a part coöperating with the apertures in the tube to control the admission of air thereto, said member also being provided with a longitudinal passage, and with a needle mounted in said longitudinal passage, and a fuel nozzle with which said needle coöperates to control the supply of fuel to said passage, said passage being connected to the atmosphere so that it can receive a small supply of air, said nozzle having an opening in its upper surface and said needle projecting into said opening in said nozzle.

6. In a carbureter, the combination of a tube having a lateral air inlet aperture, a member slidable longitudinally within said tube and provided with a perforated part coöperating with the aperture in the tube to control the admission of air thereto, said member also being provided with a longitudinal passage, with a needle mounted in said longitudinal passage, and with a cap located at the top of said passage and provided with restricted perforations for allowing the flow of fluid from said passage to the space 115 within said tube, and a fuel nozzle with which said needle coöperates to control the supply of fuel to said passage, that end of said passage which is opposite said cap being connected to the atmosphere so as to receive a small supply of air.

7. In a carbureter, the combination of a tube having a lateral air inlet aperture, a member manually slidable longitudinally within said tube and provided with a perforated part coöperating with the aperture in the tube to control the admission of air thereto, said member also being provided

with a longitudinal passage, and with a needle mounted in said longitudinal passage, and a fuel nozzle with which said needle coöperates to control the supply of fuel to said passage, said passage and said tube, both being smooth interiorly so as to prevent eddying, said nozzle having an opening in its upper surface and said needle projecting into said opening in said nozzle.

10 8. In a carbureter, the combination of a tube having a lateral air inlet aperture, a member slideable longitudinally within said tube and provided with a perforated part coöperating with the aperture in the tube to control the admission of air thereto, said member also being provided with a longitudinal passage, with a needle mounted in said longitudinal passage, and with a cap located at the top of said passage and provided with perforations for allowing the flow of fluid from said passage to the space within said tube, a fuel nozzle with which said needle coöperates to control the supply of fuel to said passage, and a heating coil located in said tube above said slideable member and into the lower end of which said cap projects so that the discharge through the perforations of said cap will be to the interior of said coil.

9. In a carbureter, the combination of a mixing tube, a fuel nozzle therein, a needle coöperating with said nozzle to control the flow of fuel therethrough, and a support for said needle which support has a greater co-efficient of expansion than has said tube.

10. In a carbureter, the combination of a mixing tube, a fuel nozzle therein, a needle coöperating with said nozzle to control the flow of fuel therethrough, and a support for said fuel nozzle which support has a greater co-efficient of expansion than has said tube.

11. In a carbureter, the combination of a conduit, a valve controlling a supply of air to said conduit, a tube of comparatively small cross-section and great length, one end

of said tube discharging into said conduit through a contracted opening smaller than the tube itself and the other being supplied with air in small quantity as compared with the air supplied through said valve, a fuel nozzle located in said tube at a point remote from its discharge end, and a needle coöperating with said fuel nozzle to furnish a fuel valve.

12. In a carbureter, the combination of a conduit, a manually operated valve controlling a supply of air to said conduit, a tube of comparatively small cross-section and great length, one end of said tube discharging into said conduit and the other being supplied with air in small quantity as compared with the air supplied through said valve, a fuel nozzle located in said tube at a point remote from its discharge end, and a needle projecting into said fuel nozzle to furnish a fuel valve.

13. In a carbureter, the combination of a conduit, a manually operated valve controlling a supply of air to said conduit, a tube of comparatively small cross-section and great length, one end of said tube discharging into said conduit and the other being supplied with air in small quantity as compared with the air supplied through said valve, a fuel nozzle located in said tube at a point remote from its discharge end, and a needle coöperating with said fuel nozzle to furnish a fuel valve, said fuel valve and said first-named valve being interconnected so as to be operated together and the extent of opening of the two valves being substantially proportional at all positions.

In witness whereof, I have hereunto set my hand at Indianapolis, Indiana, this 25th day of August A. D. one thousand nine hundred and fourteen.
